Primary Examiner — John R Yeh*(74) Attorney, Agent, or Firm* — LEYDIG, VOIT & MAYER, LTD.(57) **CLAIM**

The ornamental design for a steam mop, as shown and described.

DESCRIPTION

FIG. 1 is a top-left perspective view of a steam mop showing my new design;

FIG. 2 is a left side view thereof;

FIG. 3 is a right-side view thereof;

FIG. 4 is a front view thereof;

FIG. 5 is a rear view thereof;

FIG. 6 is a top view thereof; and,

FIG. 7 is a bottom view thereof.

The broken lines in the drawings depict portions of the steam mop that form no part of the claimed design.
